UNITED STATES PATENT OFFICE.

EUGENE DE KLEIST, OF NORTH TONAWANDA, NEW YORK.

EXPRESSION DEVICE FOR PNEUMATIC MUSICAL INSTRUMENTS.

No. 889,467.

Specification of Letters Patent.

Patented June 2, 1908.

Application filed June 18, 1906. Serial No. 322,164.

To all whom it may concern:

Be it known that I, EUGENE DE KLEIST, a citizen of the United States, and resident of North Tonawanda, in the county of Niagara and State of New York, have invented a new and useful Improvement in Expression Devices for Pneumatic Musical Instruments, of which the following is a specification.

This invention relates to the regulating devices employed in pneumatic musical instruments for causing the same to shade the music or play with expression, and more particularly to expression devices in which the desired effects are produced by varying the air tension or degree of vacuum in the wind chest.

The object of my invention is the provision of an efficient and inexpensive expression device of this character which can be conveniently regulated and which is not liable to get out of order.

In the accompanying drawings consisting of 2 sheets: Figure 1 is a sectional front elevation of a self playing pneumatic piano, embodying the invention, the piano action and other members not constituting a part of the improvement being omitted. Fig. 2 is a diagrammatic cross section of the wind chest, the tracker board and the expression mechanism, on an enlarged scale, the plane of the section of the expression mechanism being in line 2—2, Fig. 4. Fig. 3 is a front view of the expression mechanism. Fig. 4 is a rear view of the said mechanism, with its rear board omitted. Fig. 5 is a horizontal section in line 5—5, Fig. 4.

Similar letters of reference indicate corresponding parts throughout the several views.

A indicates the wind chest containing a pneumatic action of any suitable construction and B the motor pneumatics which operate the usual abstracts or stickers which act upon the piano-action, not shown.

C indicates the pumps or main suction bellows which may be operated by an electric motor or other suitable means, and D is the usual collapsible reservoir. In the construction shown in the drawings, the pumps are connected with a horizontal wind board or chamber E, and the main exhaust channel F of the wind chest is connected with this wind board by tubes f.

G is a tracker board of ordinary construction, G¹ the traveling music sheet wound upon the rolls h, h¹, and I the usual tubes or

conduits leading from the ducts of the tracker board to the wind chest.

J is a valve box or case containing a plurality of inlet or flushing chambers j, j¹, j² and an outlet or regulating chamber j³, the valve box being divided to form these chambers by a longitudinal partition k and transverse partitions k¹. The regulating chamber j³ is connected with the chamber of the wind board E by a tube j⁴. Each of said flushing chambers communicates with the regulating chamber by a port l formed in the longitudinal partition k and controlled by an automatic regulating valve l¹ of any suitable construction which opens toward the regulating chamber, an ordinary hinged or swinging valve being shown in the drawings. Each regulating valve is yieldingly held closed by a spring l² applied to its screw threaded stem l³ between an adjustable button or nut l⁴ and a bridge piece l⁵ which spans the corresponding port l, the valve stem passing through said port and bridge piece.

Each of the flushing chambers j, j¹, j² is provided with a port m by which it communicates with the outer atmosphere and which is controlled by a valve m¹, preferably of the rocking type shown. These ports are preferably formed in the top of the valve box and their valves m¹ are normally closed by suitable springs, as shown. When one of the valves m¹ is opened by the means herein-after described, the outer atmosphere enters the corresponding flushing chamber and by its pressure against the corresponding regulating valve l¹ opens the same to the extent permitted by its resistance spring l². The atmosphere is thus admitted to the regulating chamber j³ and thence to the wind board E and the wind chest, thereby diminishing the tension or degree of vacuum in the latter, operating the motor pneumatics with correspondingly less force and causing the piano hammers to strike the strings more lightly. The springs l² of the regulating valves l¹ are so tensioned or graded that they respectively exert the necessary resistance upon the valves to produce different air tensions corresponding for example to piano, mezzo forte and forte.

The regulating valve or valves which have springs of low resistance have a tendency to flutter. To prevent this a light, supplemental spring l⁶ is arranged to bear against the outer end of the stem or the adjusting

nut of each of such valves, two of the valves being provided with such springs in the construction shown in the drawings. If desired, only the valve of lowest resistance may 5 be provided with such an auxiliary spring. These auxiliary springs do not interfere with the action of the resistance springs of said valves, but simply serve to prevent vibration of the latter while open.

- 10 N, N¹, N² indicate a plurality of expression pneumatics or bellows which respectively control the flushing valves m¹. In the construction shown, these pneumatics are mounted on a shelf n arranged above said 15 valves and their upper movable boards act upon the tails of the valves through the medium of rods or stickers n¹, so that when one of said pneumatics is collapsed, the corresponding flushing valve is opened, while 20 when the pneumatic is flushed, the valve is closed by its spring, in an obvious manner. Each of the expression pneumatics N, N¹, N² is controlled by a row of perforations in the music sheet and a corresponding valve 25 mechanism of the wind chest, like the valve mechanisms which control the motor-pneumatics of the piano hammers. In Fig. 2 is shown one of these valve mechanisms, which comprises the customary double puppet 30 valve o, o¹, controlling the usual air and exhaust ports o², o³ which communicate respectively with the air chamber o⁴ and the exhaust chamber F of the wind chest, the pneumatic being connected by a tube p with 35 the exhaust and flushing channel p¹ of the corresponding valve mechanism. When a perforation of the music sheet registers with the tracker duct corresponding to one of said expression pneumatics, the corresponding 40 puppet valve is elevated or reversed in a well known manner, placing said pneumatic in connection with the exhaust chamber of the wind chest and collapsing it, while when an imperforate portion of the music sheet passes 45 over said duct, the puppet valve descends, placing the pneumatic in communication with the air chamber o⁴ of the wind chest and flushing it. It will be understood that the 50 music sheet has a separate row of perforations for each of the expression pneumatics.

With each expression pneumatic preferably co-operates a retaining pneumatic or bellows q which locks the movable board of the expression pneumatic in its depressed 55 position during the period it is to remain collapsed, thereby avoiding the necessity of providing the music sheet with long slots for this purpose. In the construction shown, these retaining pneumatics are 60 mounted vertically on a wall or board R secured to the front side of the valve box J and the movable board of each of the same is provided with a catch having a shoulder s which interlocks with a bar s¹ carried by the 65 movable board of the corresponding expres-

sion pneumatic when the latter is collapsed and the retaining pneumatic is expanded, as shown by dotted lines in Fig. 2. When the retaining pneumatic is collapsed, its catch is withdrawn from engagement with the movable board of the expression pneumatic, allowing the latter to expand to its former position. The catch of each retaining pneumatic is preferably provided above its main shoulder s with an auxiliary shoulder or stop s² which interlocks with the bar s¹ of the corresponding pneumatic when the latter is expanded, thereby limiting the expanding movement of the expression pneumatic. The retaining pneumatics are controlled by separate rows of perforations in the music sheet and co-operating valve mechanisms in the wind chest, identical with those which control the motor pneumatics and the expression pneumatics, the letter t indicating the tubes which connect the retaining pneumatics with the corresponding exhaust and flushing channels of the wind chest.

The operation of the expression mechanism is as follows: The pumps C are of such size and operated at such a speed as to produce an air tension or degree of vacuum in the wind chest sufficient to give a maximum force of stroke to the greatest number of piano hammers actuated at a time. So long as none of the expression perforations of the music sheet register with the tracker ducts, the expression pneumatics N, N¹, N² remain expanded and the flushing valves m¹ remain closed. Under these conditions, the outer atmosphere is excluded from the flushing chambers j, j¹, j² and prevented from acting upon the regulating valves l. The latter therefore all remain closed and the maximum air tension is produced in the regulating chamber j³ and the wind chest, causing the instrument to play quite loud, say double forte. When a perforation in the music sheet controlling say the expression pneumatic N registers with the corresponding tracker duct, the pneumatic is collapsed, opening the companion flushing valve m¹ and allowing the atmospheric pressure to act upon the corresponding regulating valve l¹ and open the same. The resistance of this valve is such that when the same is opened the tension in the wind chest is reduced to the proper extent to produce a comparatively loud effect, say forte. When the flushing valve controlled by the second expression pneumatic N¹ is in like manner opened, the atmospheric pressure opens the corresponding regulating valve, the resistance of which is such as to reduce the air tension to the necessary extent to cause the instrument to play a degree softer, say mezzo forte, while when the flushing valve controlled by the third pneumatic N² is opened, the consequent opening of the 130

companion regulating valve by the atmospheric pressure produces the lowest air tension, which causes the instrument to play quite softly, say piano. Three expression 5 pneumatics and three regulating valves are herein shown, but it is obvious that a greater or less number may be employed, according to the number of shades of expression desired.

10 While I have herein shown and described pneumatic means for controlling the flushing valves, I do not wish to be limited to that construction, as the same could be operated manually or by mechanical or 15 other suitable means without departing from the scope and spirit of the invention.

I claim as my invention:

1. A device for controlling the air tension of pneumatic musical instruments, 20 comprising a case having a plurality of flushing ports and a plurality of corresponding regulating ports, valves controlling said regulating ports and having resistance devices of different tensions, valves controlling 25 said flushing ports, and means for operating said flushing valves, substantially as set forth.

2. A device for controlling the air tension of pneumatic musical instruments, comprising 30 a case containing a plurality of independent flushing chambers each having an inlet or flushing port and an outlet or regulating port, valves controlling the respective regulating ports and having resistance devices of 35 different tensions, individual valves controlling said flushing ports, and means for operating the last-named valves, substantially as set forth.

3. A device for controlling the air tension 40 of pneumatic musical instruments, comprising a case having a plurality of flushing ports and a plurality of corresponding regulating ports, valves controlling said regulating ports and having resistance devices of different 45 tensions, valves controlling said flushing ports, and pneumatics for operating said flushing valves, substantially as set forth.

4. A device for controlling the air tension 50 of pneumatic musical instruments, comprising a case containing a regulating chamber and a plurality of flushing chambers connected with the regulating chamber by individual regulating ports, each flushing chamber

ber also having a flushing port, automatic valves controlling said regulating ports and 55 having closing springs of different grades of resistance, valves controlling said flushing ports, and means for operating the last-named valves, substantially as set forth.

5. A device for controlling the air tension 60 of pneumatic musical instruments, comprising a case containing a regulating chamber and a plurality of flushing chambers connected with the regulating chamber by individual regulating ports, each flushing chamber 65 also having a flushing port, bridge pieces extending across the regulating ports, valves controlling said regulating ports and having stems which pass through said bridge pieces, adjusting nuts mounted on said stems, resistance springs applied to said valve stems between the bridge pieces and said nuts, and valves controlling said flushing ports, substantially as set forth.

6. A device for controlling the air tension 75 of pneumatic musical instruments, comprising a case containing a plurality of independent flushing chambers each having an inlet or flushing port and an outlet or regulating port, valves controlling the respective regulating ports and having resistance devices of 80 different tensions, valves applied to said flushing ports, expression pneumatics controlling the last-named valves, and retaining pneumatics for locking the expression pneumatics in their collapsed position, substantially as set forth.

7. A device for controlling the air tension 85 of pneumatic musical instruments, comprising a case containing plurality of independent 90 flushing chambers each having an inlet or flushing port and an outlet or regulating port, valves controlling the respective regulating ports and having closing springs of different 95 tensions, one or more of said valves being provided with auxiliary springs to prevent fluttering thereof when open, valves applied to said flushing ports, and means for operating the last named valves, substantially as set forth.

100 Witness my hand this 14th day of June, 1906.

EUGENE DE KLEIST.
